UNITED STATES PATENT OFFICE.

WILLIAM H. BULLOCK, OF OSWEGO, NEW YORK.

MATCHING-MACHINE.

SPECIFICATION forming part of Letters Patent No. 555,495, dated March 3, 1896.

Application filed September 13, 1895. Serial No. 562,399. (No model.)

To all whom it may concern:

Be it known that I, WILLIAM H. BULLOCK, of Oswego, in the county of Oswego, in the State of New York, have invented new and 5 useful Improvements in Matching-Machines, of which the following, taken in connection with the accompanying drawings, is a full, clear, and exact description.

My invention relates to machines for matching lumber for tongue-and-groove jointing, and my object is to produce a machine in which a board of any width is fed into the machine, is slotted by multiple saws into strips of the desired width, and the edges of each of 15 these strips are cut with a tongue and groove without separating said strips apart horizontally or changing their longitudinal alignment from that of the board as fed to the saws, but in which the strips are alternately 20 shifted into different parallel horizontal planes as fast as they are fed, so that a rotating cutter will come between each pair of strips to either cut a tongue or a groove in the parallel edges of the alternate strips, such 25 cutters being arranged alternately above and below the plane of the board as it is fed, means being provided which spring the strips alternately above and below said plane into proper 30 relation to the cutters; and in which, in case the lumber is thick, it can be resawed, as by a horizontal saw, then slotted longitudinally into strips of the desired width, arranged in pairs, and by suitable cutters the edges of each strip of each pair are tongued and grooved 35 simultaneously; all so that by one handling a board is fed into the machine, cut into strips of the desired width and resawed into the desired thickness if desired, and all of the strips are tongued and grooved before leaving it. 40 Thus a board can be slotted into four strips and each of these strips can be tongued and grooved simultaneously, whereas by the ordinary way the board and each strip must be separately handled; and in case a board is 45 resawed and then slotted by three saws, eight strips are produced, and these are all tongued and grooved simultaneously, and by the single handling of feeding the board into the machine, while by the ordinary way the board

and each of the strips must be separately 50 handled to be fed into the machine, to be first cut to width and then tongued and grooved.

My invention consists in the several novel features of construction and operation which are hereinafter described and which are specifically set forth in the claims hereunto annexed.

It is constructed as follows, reference being had to the accompanying drawings, in which—

Figure 1 is a longitudinal vertical sectional 60 elevation of the feed-rollers, slitting-saw, strip-pressing rollers, strip-separating wedge, tenon and groove cutters, and showing by the dotted lines a resawing saw, and showing a board passing through, being slotted into 65 strips, the strips forced into different horizontal planes, and the cutters in operation upon their edges. Fig. 2 is a sectional elevation of four strips and four strip-pressing rollers for forcing them into different planes, on 70 line z , Fig. 1. Fig. 3 is a vertical sectional elevation on line y in Fig. 1, showing four strips being tongued and grooved. Fig. 4 is a like view showing four strips resawed into eight strips and all being tongued and grooved by 75 double cutters simultaneously.

Inasmuch as the different shafts and rollers are all journaled in ordinary bearings, and these can be mounted upon any suitable frame of any desired construction, and because such frame and bearings are no part of my invention, I have not shown them in the drawings, as any intelligent mechanic can readily construct them.

Suitable feed-rollers 2 are secured upon 85 suitably-journalized shafts 3, and 4 is a board being fed through between said rollers. A suitable surface-planer 5, mounted upon a suitable shaft 6, can be used when it is desired to plane the top of the board, and a like 90 planer can be suitably mounted so as to plane the lower side thereof when it is desired to plane both sides, as when the board is to be resawed.

The dotted lines 7 indicate a suitable resawing-saw and shaft which can be used when desired. Upon a suitably-journalized shaft 8 slitting-saws 9 are mounted in such manner

that they can be adjusted according to the width of the strips to be cut, and these leave the strips 10 all in the same horizontal plane.

Upon suitably-journalized shafts 11 rollers 12 13 are secured alternately above and below and bearing upon the alternate strips to force one down and the next one up into different planes and separating the ends of the strips, so that the first on the left will pass 10 under the wedge-separator 14, the next strip will pass over it, and so on. The result of all this is that the strips are thus separated vertically, so that the cutters 15 16 can have access to and cut the tongues and grooves in all 15 the strips simultaneously. These cutters are all of ordinary construction and are mounted, the cutters 15 upon suitable vertical shafts 17, suitably mounted above the strips, and the cutters 16 upon suitably-journalized shafts 20 18 under the strips, all being so arranged that the upper cutters are in the proper plane to tongue and groove the upper strips and the lower cutters to tongue and groove the lower strips, all without laterally separating the 25 strips.

Suitable feed-rollers 19 are suitably mounted upon suitably-journalized shafts in front and rear of the cutters and also above and below the strips, all bearing upon and holding the strips onto that position of the separator rearward from the wedging portion and where the faces are parallel.

In order to insure the perfect cutting of the corners of the strips, the inner ends of the 35 cutters are recessed into the separator and their outer ends project beyond the outer faces of the strips, as respectively shown at 20 and 21 in Fig. 4.

In Fig. 4 the cutters are shown as double 40 and each tonguing and grooving two strips, as where the lumber is resawed, so that four double cutters are simultaneously finishing eight strips.

It will thus be seen that the principle of my 45 invention is the vertical separation by a suitable wedge, or by a wedge and rollers, of the several strips without moving them laterally, except possibly where the strips are too narrow to permit the insertion and operation of 50 a cutter between two strips which lie in the same plane.

It will also be seen that where desired the slitting-saw can be omitted and the previously-sawed strips can be fed into the machine with their adjacent edges in contact,

and that they will then be alternately sprung into different planes and tongued and grooved as aforesaid, and that such previously-sawed strips, when fed in can be resawed, if desired.

In Fig. 5 I show a mechanism for guiding 60 the strips without spreading them laterally, consisting of partitions or guides 22, which are secured to brackets 23, which travel in ways 24 across the separator and are secured at any desired point according to the width 65 of the strips in any ordinary manner. These guides hold each strip in proper relation to the cutters, so that the tongue and groove of each strip will be of proper size or depth, because they prevent any lateral springing of 70 a strip.

What I claim as my invention, and desire to secure by Letters Patent, is—

1. The combination with suitable cutters arranged alternately above and below a given 75 plane, of suitable separating-rollers whereby alternate strips of lumber are spread vertically into the planes of the cutters, whereby the opposite edges of the respective strips are simultaneously tongued and grooved. 80

2. The combination with suitable feed-rollers between which a piece of lumber is fed and a slitting-saw to cut it into strips, of separating-rollers whereby alternate strips are spread vertically into parallel planes, and 85 cutters arranged to cut the edges of any two strips in the same plane simultaneously.

3. The combination with suitable feed-rollers between which a piece of lumber is fed, a slitting-saw to cut it into strips and a resaw- 90 ing-saw to cut the lumber horizontally, of separating-rollers whereby alternate pairs of strips are spread vertically into different planes and double cutters arranged to cut the edges of all the pairs of strips simultaneously. 95

4. The combination with suitable cutters arranged alternately above and below a given plane, of suitable separating-rollers whereby alternate strips of lumber are spread vertically into the planes of the cutters, and guides 100 22 which engage with the edges of said strips to hold them relatively to said cutters against lateral deflection.

In witness whereof I have hereunto set my hand this 26th day of August, 1895.

WILLIAM H. BULLOCK.

In presence of—

C. W. SMITH,
JESSIE E. MURRAY.
